UNITED STATES PATENT OFFICE.

JAMES C. DAWSON, OF WEBSTER GROVES, MISSOURI.

BOOKBINDING.

1,358,421.

Specification of Letters Patent.

Patented Nov. 9, 1920.

Application filed May 5, 1919. Serial No. 294,770.

To all whom it may concern:

Be it known that I, JAMES C. DAWSON, a citizen of the United States, and resident of Webster Groves, county of St. Louis, and 5 State of Missouri, have invented certain new and useful Improvements in Bookbinding, of which the following is a specification, and which are illustrated in the accompanying drawings, forming a part 10 thereof.

The invention relates to the art of book binding and has for its object the provision of an inexpensive but permanent binding, including both covers and back, for loose 15 sheets which may be conveniently used when the preservation of a quantity of such sheets is required but only occasional reference to the sheets is anticipated.

To this end the invention contemplates a 20 construction in which the sheets are secured between separate covers after which the back is formed to protect the ends of the sheets at the back of the volume.

Further features of the invention will be 25 described in connection with the construction shown in the accompanying drawings, in which—

Figure 1 is a perspective view showing a 30 bound volume made in accordance with the invention;

Fig. 2 is a perspective view showing a bound volume prior to the formation of the back;

Fig. 3 is a view similar to Fig. 2 showing 35 another form of fastening;

Fig. 4 is a view similar to Fig. 2 showing still another form of fastening; and

Fig. 5 is a detail sectional view through one of the back forming flaps.

40 In carrying out the invention a quantity of the sheets to be preserved are collected together to form a stack 10. Covers, as 11 and 12, are then applied to the stack 10 upon opposite sides of the same. The covers 45 11 and 12 are preferably of like construction and each cover is desirably formed from inexpensive soft materials as a layer of binder's board inclosed in canvas. To facilitate the future examination of the 50 sheets the binder's board is preferably omitted in each cover 11, 12, upon a line adjacent to and parallel with one end of the cover, thereby forming a hinge 13.

The covers may be secured to the sides of 55 the stack 10 in a variety of ways, three suitable methods being illustrated in Figs. 2, 3

and 4. In the method shown in Fig. 2 sharp nails 14 are forced into the stack 10 from opposite sides, through the corresponding cover. If the nails, as shown, are of such 60 length as to pass completely through the stack and the opposite cover the projecting ends 14^a should preferably be cut off, after insertion, flush with the outer surface of the cover on the far side instead of clenching. There are no openings for receiving the nails 14 either in the covers 11, 12, or in the sheets forming the stack prior to the entry of the nails. The nails are frictionally held throughout their length with sufficient force to prevent the subsequent separation of the sheets by any ordinary method of handling the completed volume.

In the method shown in Fig. 3 the covers and the sheets forming the stack are 75 punched and through these apertures a wire 15 of U-shape is inserted and its ends subsequently turned over or clenched as at 15^a. Metallic plates 16 and 17 are preferably provided for distributing and equalizing 80 the pressure of the wire on the covers. In the method shown in Fig. 4 the covers and the sheets forming the stack are punched and through these apertures cords or tapes are passed, the ends of which are drawn 85 taut and knotted at 19.

To form a back for the bound volume flaps 20 are provided on each cover. These flaps are attached by adhesive, sewing or other means to the faces of the covers along 90 one edge thereof, preferably with one edge registering with an edge of the cover and the opposite edge normally extending toward the opposite edge of the cover. The fastening devices, whether nails, wire, cords 95 or tape, are arranged to pass through that part of each flap 20 which is secured to the cover so that when the flap is folded rearwardly to form the back, as shown in Fig. 1, the fastening devices are entirely concealed. 100 As the flaps are preferably formed of stiff material they are scored along the lines where they are folded rearwardly and where they are folded over the edges of the covers to facilitate bending.

105 As the stacks to be bound will vary in height the flaps 20 are preferably made long enough to pass across the back of the highest stack likely to be bound and reach the edge of the opposite cover. For smaller sized 110 stacks the flaps are cut to the desired length and to facilitate cutting them evenly lines

21 may be printed and scored or simply scored on the inner face of the flaps. After cutting to the requisite length one flap is secured to the back of the stack by adhesive 5 which may be conveniently applied to each flap at the time the covers are manufactured. The flap on the opposite cover is then gummed onto the outer face of the first flap so that the finished volume has the form 10 and appearance shown in Fig. 1.

As there is considerable strain and wear on those edges of the flaps which extend between the covers, these edges are preferably bound over with a fabric strip 22 as 15 illustrated more particularly in Fig. 5.

I claim as my invention:

1. The method of binding loose sheets to form a permanent record volume which consists in assembling the sheets in a stack, applying 20 a flexible cover and flap to each side of the stack, forcing a plurality of sharp nails into the stack from opposite sides of the same near one edge through the corresponding covers and flaps without previous 25 perforation of the sheets or covers in line with the nails and without clenching the nails, folding said flaps each upon itself so as to cover the nails and about the back of the volume and gumming one flap to the 30 back edges of the sheets in the stack and the other flap to the first named flap.

2. In a book, in combination, a stack of sheets, a pair of covers applied to opposite sides of the stack of sheets, fastening devices 35 for securing one edge of each of the covers to the stack, and a back forming flap secured to one cover adjacent said edge, with its free end normally extending toward the 40 opposite edge of the same cover but adapted to be folded back and to be secured by adhesive to the back edges of the sheets in the stack.

3. In a book, in combination, a stack of sheets, a pair of covers applied to opposite 45 sides of the stack of sheets, fastening devices for securing one edge of each of the covers to the stack, and a back forming flap secured to one cover adjacent said edge, with its free end initially extending toward the

opposite edge of the same cover and folded 50 back and secured by adhesive to the back edges of the sheets in the stack, the ends of the fastening devices being between the cover and the backwardly folded portion of the flap when the latter is in back-forming 55 position.

4. In a book, in combination, a stack of sheets, a pair of covers applied to opposite sides of the stack of sheets, fastening devices for securing one edge of each of the 60 covers to the stack, and back forming flaps secured to the covers adjacent said edges with their free ends initially extending toward the opposite edge of the cover to which they are attached and folded back 65 and secured by adhesive to the back edges of the sheets in the stack and to the opposite flap respectively, the ends of the fastening devices being between the cover and the backwardly folded portions of the flaps 70 when the latter are in back forming position.

5. In a book, in combination, a stack of sheets, a pair of covers applied to opposite sides of the stack of sheets, a back-forming 75 flap secured to the back edge of one of said covers with its free end initially extending toward the opposite edge of the same cover, fastening devices for securing one edge of each of the covers and of the flap to the 80 stack, the initially free portion of the flap folded upon the secured portion and secured by adhesive to the back edges of the sheets in the stack and to the secured end of the 85 opposite cover.

6. The method of binding loose sheets to form a permanent volume which consists in assembling the sheets in a stack, applying a cover and flap to each side of the stack of sheets, introducing fastening devices 90 through the stack of sheets and covers near one edge of the stack of sheets, folding said flaps each upon itself to cover the fastening devices and the back of the volume and adhesively securing the flaps to the back edges 95 of the sheets in the stack.

JAMES C. DAWSON.
